Inventors,
Charles Linden
Walter Tronk
By M. N. Loughridge, Attorney

UNITED STATES PATENT OFFICE.

CHARLES LINDEN AND WALTER TRONK, OF SOUTH AMBOY, NEW JERSEY.

FOUNTAIN PEN.

Application filed January 6, 1925. Serial No. 789.

To all whom it may concern:

Be it known that we, CHARLES LINDEN, a citizen of the United States, and WALTER TRONK, a citizen of the Republic of Germany, residing in South Amboy, in the county of Middlesex and State of New Jersey, have invented certain new and useful Improvements in Fountain Pens, of which the following is a specification.

10 This invention relates to fountain pens and has for an object to provide a visual indicator of the ink reservoir so that by inspection the time for refilling can readily be determined. This invention is shown applied to the so called "self filling" type of fountain pens, is comparatively inexpensive and can be applied with very little change to the ordinary type of fountain pen.

The objects of the invention will be more particularly understood from the following specification and the accompanying drawings in which, Fig. 1 is a section view of a fountain pen of the usual type to which our invention has been applied, Fig. 2 is a view 25 of the pen complete and Fig. 3 is a detail, partly in section, showing an alternative construction in the application of our invention. Fig. 4 is a section on the line 4—4, Fig. 3.

In the ordinary type of fountain pen the flow of ink is often impeded and it is impossible to tell if this is due to want of ink in the reservoir or to stoppage of the ink passage. In the present invention part of the ink reservoir is transparent and suitable 35 windows or apertures are provided in the barrel of the pen by which the transparent part of the reservoir and thus the ink supply is open to inspection.

In the self filling pens the ink reservoir is 40 usually made of rubber tubing which is easily collapsed for refilling purposes. In applying our invention we have removed a section of this rubber tubing and substituted glass tubing therefor and opposite this 45 glass tube a slot is milled through the barrel of the pen so that a "sight" may be taken through the glass tube from which the height of the ink in the reservoir is determined. The slots in the barrel of the pen 50 may be left open or they may be protected by an outer transparent ferrule or by a rotating sleeve.

55 Referring to the drawings, 11 is the barrel of the pen, 12 is the stub screwed into the barrel at 13 and 14 is the writing point. The stub 12 terminates in the shank 15 and by

the rubber tubing 16 connects with the glass tube 17 and the glass tube, in turn, connects with the rubber tube 18. The tubes 16, 17 and 18 form the ink reservoir. The slots 19 and 20 in the barrel 11 align with the transparent tube 17 as shown in Fig. 1. These slots are protected by the transparent ferrule 21 so that dust cannot enter the interior of the barrel and in case of leakage of the ink reservoir the ink cannot smear the outside of the pen. The parts to which the rubber tubing connects are preferably corrugated as indicated on the drawing and the rubber tubing may be cemented or otherwise fastened to the rigid parts.

The self filling lever is indicated at 22. When this lever is moved outwards the flat spring 23 compresses the tube 18 preparatory to drawing in a new supply of ink. This is the usual construction in pens of this type and the operation is not interfered with by the glass tube 17.

The construction in Fig. 3 shows a rotating sleeve for covering the slots 19 and 20. This sleeve 24 is rotated by the knurled end 25 and has a pair of diametrically opposed slots at 26 which can be brought into line with 27 and 28 and thus expose the glass tube in the ink reservoir.

It will be noted that when the pen is held vertically the transparent tube is near the bottom of the reservoir and thus shows when the supply of ink is low. Attention is called to the fact that by sighting the ink through the tube there is no dark background against which the ink would be difficult to see.

When the stub 12 is removed the reservoir is removed with it thus facilitating inspection, cleaning and renewals.

This invention may be applied to an ordinary self-filling fountain pen simply by milling the slots 19 and 20 in the barrel and inserting a section of glass tube in the ink reservoir.

Having thus described our invention, we claim:

1. In a fountain pen of the class described, the combination of a barrel having a pair of diametrically opposed slots with a detachable ink reservoir in said barrel, a transparent section in said reservoir, said transparent section being opposite said slots.

2. In a fountain pen of the class described, the combination of a barrel having a slot in its side with an ink reservoir in said barrel, said reservoir comprising a portion of rub-

ber tubing and a transparent portion, said transparent portion being opposite said slot.

3. In a fountain pen of the class described, the combination of: a barrel having a slot in its side, a transparent cover for said slot and a detachable ink reservoir in said barrel, said reservoir having a transparent section opposite said slot.

4. In a fountain pen of the class described, 10 the combination of a barrel having a pair of diametrically opposed slots, a ferrule for protecting said slots and a detachable ink reservoir in said barrel, said reservoir having a transparent section opposite said slot.

5. In a fountain pen of the class described, 15 the combination of a barrel having a slot in its side, a stub secured to the end of said barrel and an ink reservoir secured to said stub, said reservoir comprising a section of rubber tubing, a section of glass tubing and 20 a second section of rubber tubing closed at one end, said glass tubing being located opposite said slot.

Signed at South Amboy, Middlesex County, New Jersey, this 31st day of October, 25 1924.

CHARLES LINDEN.
WALTER TRONK.
